UNITED STATES PATENT OFFICE.

WALTER SCOTT PHELPS, OF WORTENDYKE, NEW JERSEY.

STEAM-ACTUATED VALVE.

SPECIFICATION forming part of Letters Patent No. 313,684, dated March 10, 1885.

Application filed March 17, 1884. (No model.)

To all whom it may concern:

Be it known that I, WALTER S. PHELPS, of Wortendyke, in the county of Bergen and State of New Jersey, have invented new and 5 Improved Steam-Actuated Valves for Steam-Cylinders, of which the following is a full, clear, and exact description.

The object of my invention is to provide new and improved steam-actuated valves for 10 the steam-cylinders of steam-engines, steam-pumps, &c.

The invention consists in the combination, with a steam cylinder and piston, of a steam-chest containing a series of pistons which are 15 operated by the live steam in the cylinder at the end of each stroke, which live steam, after being admitted into the chest, works under expansion and shifts the pistons, all as will be fully described and set forth hereinafter.

Reference is to be had to the accompanying drawings, forming part of this specification, in which similar letters of reference indicate 20 corresponding parts in all the figures.

Figure 1 is a side view of a steam-pump provided with my improved valve. Fig. 2 is a 25 cross-sectional elevation of the same on the line $x x x x$, Fig. 3. Fig. 3 is a longitudinal sectional elevation of the steam-cylinder and the valves. Fig. 4 is a cross-sectional elevation on the line $y y$, Fig. 3. Figs. 5, 6, and 30 7 are sectional diagrams showing the different relative positions of the piston and the slide-valve.

A is the steam-piston, working in a cylinder, 35 B, and secured to a piston-rod, A', which is connected with a pump-piston or with a crank. C is the steam-supply pipe. D is the exhaust-pipe; and E represents a steam-chest held detachably by screws or bolts on the top of the 40 cylinder, which chest E contains the entire valve mechanism. Both ends of chest E are constructed alike, and it can easily be reversed, so that either end will project toward the pump; or it can be placed transversely on 45 the cylinder, as the ports, &c., which will be described hereinafter, and which have their ends in the bottom of the chest E and in the top of the cylinder B, are arranged in segmental lines, so that if the chest E is revolved 50 on its vertical axis and on the vertical central

axis of the cylinder the ports of the cylinder and of the chest E will always coincide. The cylinder B is provided with two channels, b and b', which lead from the extreme ends of the cylinder to the flat portion of the upper outer surface of the cylinder, the upper ends of the channels b and b' being brought quite close together, and between them the channel d is arranged, which projects upward from the exhaust-pipe D to the said flat portion of 55 the upper surface of the cylinder.

A short distance from each end of the cylinder, which distance is a trifle greater than the thickness of the piston, channels c and c' lead to the flat upper surface of the cylinder. The 60 above-described channels are arranged in the following manner on the said flat surface: In the middle is a circular channel, d. At the sides of the same and concentric with it are arranged the upper ends of the channels b and b', and concentric with and outside of the channels b and b' are the channels c and c'. The steam-inlet pipe C, which is screwed into the top of the chest E, is provided with a series of apertures, C', through which the steam 65 can pass into a cup or bell, C², held on the upper surface of the chest E. The live steam can pass through two or more apertures, C³, in the top of the chest into the interior of the same. Within the chest a cylinder, F, is held, 70 and in the same three cylinders, G, G', and G², are held, the cylinder G² being located in the middle of the cylinder F and the cylinders G and G' at the ends of the same. The cylinder G² is provided with exterior ribs, which 75 fit closely against the inner surface of the cylinder F, so that a series of steam-spaces will be formed between the outer surface of the cylinder G² and the inner surface of the cylinder F. Slots or other openings, g and g', at the 80 opposite end parts of the cylinder G², establish communication between the interior of the cylinder G² and the spaces between the exterior surface of the cylinder G² and the interior surface of the cylinder F. The bottom 85 apertures, g g', coincide with channels h and h', extending from the bottom of the cylinder G² to the bottom of the steam-chest E, the lower ends of the channels h and h' coinciding 90 with or fitting against the upper ends of the 95 100

channels b and b' in the cylinder B, as shown in Fig. 3.

In the bottom of the cylinder G^2 an aperture, g^2 , is formed, which coincides with the upper end of a channel, h^2 , extending down to the bottom of the chest, the lower end of the channel h^2 coinciding with the upper end of the channel d in the cylinder B.

In the bottom of the steam-chest channels j and j' are formed at the opposite ends, which channels lead from the ends of the chest E to the exhaust-channel h^2 in the bottom of the chest.

In the outer ends of the cylinders G and G' slots i and i' are formed, through which the exhaust-steam can pass from the outer ends of the cylinders G and G' to the steam-chambers between the outer surfaces of the said cylinders and the inner end surface of the steam-chest, and can then pass through the channels j and j' .

Between the outer surfaces of the cylinders G and G' and the cylinder F steam-chambers K and K' are formed, which are entirely independent of the steam-chambers between the cylinders G and G' and the cylinder F, or the cylinder G^2 and the cylinder F. Slots l and l' establish communication between the interior of the cylinders G and G' and the steam-chambers K and K' . Channels m and m' extend from the bottom parts of the steam-chambers K and K' to the bottom of the steam-chest, the lower ends of the channels m and m' coinciding with the upper ends of the channels c and c' in the cylinder. A channel, n , leads from the cup or bell C² to the steam-chamber K' , and is provided with a cock, L, for closing it.

In the cylinder G^2 a piston, H^2 , is mounted to slide, which piston is provided, between the ends, with an annular groove or recess, J, at each side of which recess packing-rings are arranged, to cause the piston to fit close within the cylinder G^2 . The said piston H^2 is mounted rigidly on a piston-rod, M, and each side of the central piston, H^2 , pistons N and N' are rigidly mounted on the said piston-rod, the said pistons N and N' being contained within the cylinders G and G' , and are provided with suitable packing-rings.

On the outer ends of the piston-rod M nuts O and O' are screwed and held rigidly, and between the said nuts and the pistons N and N' sliding pistons P and P' are loosely mounted on the piston-rod M, the said pistons being provided with a series of apertures, o and o' , parallel with the longitudinal axis of the piston. The pistons N and N' are provided on the outer ends with short cylindrical projections R and R' , in the sides of which annular grooves S and S' are formed. The heads T and T' of the steam-chest are provided in their inner surfaces with recesses t and t' , for receiving the nuts O and O' on the ends of the piston-rod M. The two end pistons in the steam-chest are provided in their rims with annular grooves w , in which the water of condensation

can collect and act as a packing for the pistons.

If desired, the exhaust-steam in the steam-chest can pass off into the air through apertures v v , in place of passing through the channels j j' .

The operation is as follows: As shown in Fig. 3, the live steam enters through the channel b in the cylinder, to the left of the piston, 75 and forces the piston in the direction of the arrow a' , the exhaust-steam in that part of the cylinder to the right of the piston being forced out through the channels b' h' , the groove J in the piston H^2 , the slot g^2 in the cylinder G^2 , 80 the channels h^2 d , and exhaust-pipe D. When the piston A arrives at the end of its stroke, as shown in Fig. 5, it almost covers the end of the right-hand channel, b' , and has passed the lower end of the channel c' , thus permitting the 85 live steam to pass through the channel c' , as indicated by the arrows. The live steam passes into the space between the adjoining ends of the pistons N' and P' , Fig. 3, and as it acts on the comparatively small surface of the piston 90 N' it moves the said piston and the rod M very gently toward the left. As the piston P' is loosely mounted on the piston-rod, it does not move with the pistons N N' H^2 . By moving the piston-rod M to the left, in the manner 95 described, the middle piston, H^2 , covers the upper end of the channel h' , and also the upper end of the channel h , as shown in Fig. 5, and the piston P' keeps the slots or apertures 100 i' closed. The steam now acts on the entire 100 end surface of the piston N' , as this end surface has been removed from the adjoining surface of the piston P' , and thereby the piston-rod M is moved still farther in the direction 105 toward the left, thus causing the central piston, H^2 , to uncover the upper ends of the channels h and h' , as shown in Fig. 6. By this time the nut O' , on the right-hand end of the piston-rod, has come in contact with the outer surface of the piston P' , and has moved the 110 same toward the left sufficiently to cover the slots or apertures l' in the cylinder G' , the slots i' still remaining covered. The outer surface of the left-hand piston, N, has struck the inner surface of the piston P , and has also 115 moved the same in the direction toward the left sufficiently to uncover the slots or apertures l in the cylinder G, and to keep the slots i in the cylinder G covered. The parts are 120 now in the position shown in Fig. 6. As the steam contained between the right-hand piston, N' , and the corresponding end of the steam-chest cannot escape, it works under expansion, and moves the piston-rod still farther toward the left. The steam contained between the 125 piston P at the left-hand end and the corresponding end of the steam-chest acts as a cushion, to prevent hammering and jarring of the steam piston and rod. By the action of the expansion of the steam the piston-rod M is 130 moved in the direction shown in Fig. 7, thus permitting the live steam to enter through the

channel b' , and move the piston in the direction of the arrow a^2 , the exhaust steam passing off through the channel b and the exhaust pipe D or openings $v v$; but by this movement 5 of the piston-rod the piston P has been moved to such an extent as to uncover the slots i' in the extreme right-hand end of the cylinder G' , thus permitting the steam contained between the outer end of the piston N' and the 10 corresponding end surface of the steam-chest to escape through the slots i' and the channel j' of openings $v v$. The left-hand parts, as shown in Fig. 7, are in the same position as the right-hand parts in Fig. 3 at the commencement of movement, and vice versa. The 15 left-hand parts, as shown in Fig. 3, are in the same position as the right-hand parts in Fig. 7, and after the piston has completed its stroke to the right the operation is repeated.

20 In addition to the above, it may be stated that as the piston-rod moves to the left the left-hand piston, N , moves the piston P in such a manner as to uncover the slots l in the cylinder G , so as to permit the live steam to pass through the channels e and m , and the slots l to act on the left-hand piston, N , when the piston A has completed its stroke to the left. The pistons P and P' are never moved directly by the piston-rod M , but always by the pistons N and N' or the nuts O and O' . The pistons P and P' must be provided with the apertures o and o' , to permit the steam that has acted on the pistons N and N' to pass to the exhaust-channels i and i' .

35 If the machine is to be started, the cock L is turned in such a manner as to admit steam into the channel K' , which steam then enters the cylinder G' through the slots or apertures i' , and forces the piston-rod M to the left. If 40 the machine stops in such a position that the live steam can act on the piston A in the main cylinder B , it will not be necessary to start the machine by opening the cock L .

Having thus described my invention, what I 45 claim as new, and desire to secure by Letters Patent, is—

1. The combination, with a steam cylinder and piston, of a steam-chest connected by channels with the steam-cylinder, and containing 50 a piston-rod on which are mounted three fixed pistons and two loose pistons at the ends, substantially as herein shown and described.

2. The combination, with a steam-cylinder, 55 of a steam-chest adjustable at any angle on the cylinder, and connected at its central part or face with suitable openings or channels in the same, said openings being semicircular in form on the face, and adapted to suit any position in which the steam-chest may be placed

60 thereon, said openings in steam-cylinder to connect with corresponding openings or apertures leading from or near the ends of the steam-cylinder, and between these openings a circular exhaust-opening, all corresponding 65 with similar openings in the face of the steam-chest, of a longitudinal piston-rod, M , in said

steam-chest, working through the central cylinder into two end cylinders separate and distinct from each other, said rod being mounted with a piston-valve upon its central part working in the central cylinder, and adapted to work alternately and connect the two opposite openings or chambers leading from the central cylinder to the ends of the main steam-cylinder with the exhaust-port of the same in connection, and having two pistons on each end of the piston-rod M , working in separate and distinct end cylinders, said pistons being comprised of a tight piston fitted upon the rod and secured on the same, and provided with a cylindrical outside surface having an annular groove, said surface fitting and covering perforated openings that pass through the loose piston, said loose piston secured by nut, key, pin, or otherwise at the extreme end of rod M of said pistons, each working alternately over a steam and exhaust port in said end cylinders, substantially as herein shown and described.

3. The combination, with the steam cylinder and piston, of a steam-chest connected by channels with the cylinder, a piston-rod in the steam-chest, a piston mounted on the center of the said piston-rod, and adapted to alternately open and close the two channels leading from the opposite ends of the cylinder into the exhaust-port, pistons mounted on the said piston-rod at each side of the middle piston, and adapted to be acted upon by steam from the main cylinder, and of sliding pistons mounted loosely on the ends of the piston-rod, and adapted to open and close the ports for the exhaust-steam that has acted on the pistons mounted on the piston-rod in the chest, substantially as herein shown and described.

4. The combination, with a steam cylinder and piston, of a steam-chest connected with the cylinder by suitable channels, a piston-rod held to move longitudinally in the steam-chest, a piston mounted on the central part of the said piston-rod, and adapted to alternately connect the channels extending from opposite ends of the cylinder with the exhaust-port, pistons mounted on the piston-rod in the chest at each side of the central piston, and adapted to be acted upon by steam from the main cylinder, pistons mounted loosely on the ends of the piston-rod in the steam-chest, and adapted to open and close the exhaust-ports for the steam that has acted upon the above-mentioned pistons on the piston-rod in the chest, and of nuts secured on the ends of the piston-rod in the chest for the purpose of operating the sliding pistons in either direction, substantially as herein shown and described.

5. The combination of a steam-cylinder constructed with openings and channels leading from the face or central port where steam-chest is secured to cylinder, said openings all being semicircular in form around the exhaust-opening, and in a proper position and of sufficient length to allow the chest to be placed on

- longitudinally crosswise or any angle from the above position, and yet retain their proper relative openings with each other for the free passage of fluids or steam back and forth, substantially as herein shown and described.
6. The combination, with a steam cylinder and piston, of the steam-chest E, the piston-rod M in the same, the central piston, H², and end pistons, N and N', provided on their outer end surfaces with cylindrical projections, substantially as herein shown and described.
7. The combination, with a steam cylinder and piston, of the steam-chest E, the piston-rod M in the same, the central piston, H², and end pistons, N and N', provided on their outer end surfaces with cylindrical projections, which projections are provided with annular grooves in their cylindrical surfaces, substantially as herein shown and described.
8. The combination, with the steam cylinder and piston, of the steam-chest on the same, the cylinders G, G', and G² in the steam-chest, of which cylinders G and G' are connected with the opposite ends of the cylinder F, and G² is connected within the cylinder F, and in connection with the steam-ports and exhaust-pipe, the piston-rod M, the piston H², mounted on the piston-rod, within the cylinder G², the pistons N and N', mounted on the piston-rod M, within the cylinders G and G', substantially as herein shown and described.
9. The combination, with the steam cylinder and piston, of the steam-chest E, the cylinder F in the same, the cylinders G, G', and G² in the cylinder F, the cylinders G and G' being provided with the slots or apertures l and i and l' and i', and the cylinder G² being provided with the slots g, g', and g'', the piston-rod M, the pistons H², N, and N', mounted rigidly on the same, and the pistons P and P', mounted loosely on the same, substantially as herein shown and described.
10. The combination, with the steam cylinder and piston, of a steam-chest connected with the cylinder by suitable channels, the piston-rod held to reciprocate in the steam-chest, a central and two side pistons fixed on the said piston-rod, which steam-chest is provided with a valved channel, n, for admitting the live steam direct from the supply-pipe, to act on one of the fixed end pistons on the piston-rod in the steam-chest, and with apertures C³, also communicating with the supply-pipe, substantially as herein shown and described.
11. The combination, with the steam cylinder and piston, of a steam-chest, the cylinder F in the same, the cylinder G², between which and the cylinder F a steam-chamber is formed which is in communication with channels leading to the opposite ends of the main cylinder, the cylinders G and G', between which and the cylinder F steam-chambers K and K' are formed, which are in communication by 65 steam-channels with the opposite ends of the main cylinder, and between which cylinders G and G' and the walls of the steam-chest steam-chambers are formed which are in communication with the exhaust-pipe, the piston-rod M in the steam-chest, the piston H², mounted rigidly on the center of the piston-rod and within the cylinder G², and the pistons N, P, N', and P', mounted on the piston-rod M, on the opposite sides of the piston H² and within the cylinders G and G', substantially as herein shown and described.
